NAILING MACHINE

Clinton J. Bacon, Los Angeles, and
Samuel J. Kent, Van Nuys, Calif.

Application March 27, 1947, Serial No. 737,510

6 Claims. (Cl. 1—46)

1

This invention relates to machines for driving nails and has for its general object to provide a nail driving machine which is automatic in operation in that nails are brought successively to a point where they are operated on by power means for rapid and efficient driving of the same.

Another object of the invention is to provide a nailing machine which is portable and embodies foot engaging means whereby said machine is moved with facility from point to point for rapid driving of nails.

Another object of the invention is to provide a machine, as indicated, having automatic means for moving nails successively from a nail hopper to a point beneath a nail driving element.

Another object of the invention is to provide a machine which embodies a novel combination of nail hopper, nail guiding means, and nail driving means arranged as a compact, easily handled machine and designed for efficient operation.

A further object of the invention is to provide a machine of the character indicated in which the nail hopper is automatically moved to cause agitation of its contents each time that a nail is driven to obviate interlocking of the nails in the hopper and to loosen them for free passage through the machine.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a longitudinal sectional view of a nail driving machine embodying the present invention and showing extended condition.

Fig. 2 is a similar view, partly in elevation, of the machine in nail driving position.

Fig. 3 is an enlarged plan sectional view taken on the line 3—3 of Fig. 1.

Fig. 4 is a cross-sectional view of the hopper as on the line 4—4 of Fig. 1.

Fig. 5 is a further enlarged cross-sectional view as on the line 5—5 of Fig. 1.

2

Fig. 6 is a fragmentary vertical sectional view on the line 6—6 of Fig. 1.

Fig. 7 is a perspective view of an escapement slide used for moving nails at one portion of their path through the machine.

Fig. 8 is a similar view of the body housing said slide.

The nailing machine which is illustrated in the drawings comprises, generally, a body 10, a nail driver 11 mounted and housed in the body, compressed air-actuated hammer means 12 also mounted and housed in the body and above the driver, an upper extension 13 of the body terminating in a handle 14 for controlling air flow through the machine, stirrup means 15 hingedly connected to the body at the lower end thereof for engagement by the foot of the user to hold the machine in operative position, a nail hopper 16, means 17 connecting the hopper and the body 10 for tilting movement of the former during operation of the machine, escapement means 18 receptive of nails from the hopper for movement thereof transversely, means 19 for guiding nails from the escapement to a position to be operated on by the driver, and detent means 20 for holding nails in said position until moved therefrom by the driver.

The body 10 comprises a barrel 21 and a plunger 22 telescopically movable therein. The barrel is formed as an elongated tube fitted in its lower end with a nose piece 23 formed with a central axial passage 24. In practice, said nose piece is fitted for relative vertical adjustment in the barrel and can be adjusted with respect to the driver, at the end of its stroke, to vary the "set" of nails being driven. Embodied in the nose piece and formed with an extension of the passage 24, there is provided an open-sided spacer 25 for upwardly and outwardly directed guide plates 26 having at least their upper edges 27 arranged at an angle to slope downwardly toward the passage 24. The plates 26 are spaced to accommodate nails passing between them and the edges 27 are chamfered for the heads of said nails which, thereby, are suspended for sliding movement toward passage 24. A spacer rider 28 is provided between the plates 26 at the lower sloping edge thereof to serve as guiding means for nails of greater length than the height of plates 26.

The plunger 22 is fitted for sliding movement in the barrel 21 and is formed of an upper extension 30 which houses the hammer means 12, and a driver guide 31. The driver 11 is integrally formed with a shank 32 designed to move in the

passage 24, a flanged shoulder 33 supported by the driver guide 31, and a head 34 engaged by the hammer means 12. Said latter means is generally conventional and comprises a suitable hammer 35 designed to be reciprocated and to engage the driver head 34 and thereby cause the driver to drive a nail residing in passage 24. Accordingly, the plunger 22 is formed with suitable air passages for effecting the mentioned percussive-inducing reciprocation of the hammer, and said plunger is movable bodily downward in the barrel to effect operative engagement of the hammer and the driver when the downward movement of the latter is arrested by the detent means 20 located across the passage 24.

The upper extension 13 comprises relatively adjustable tubular members 36 and 37 interconnected through the medium of a stuffing box 38. Said extension is formed with an air passage 39 for air from the handle 14 to the plunger 22. Said handle is also generally conventional, being mounted on the extension 13 and provided with an air inlet 40 and an air flow control trigger 41 arranged to actuate a valve 42 embodied in the handle and arranged across the flow passages therein. By bearing down bodily on the handle to telescopically move the plunger 22 to bring the hammer 35 and driver 11 into operative engagement, and actuating the trigger 41, the air will cause percussive movement of the hammer and resultant driving movement of the driver. It is evident that an electrically operated hammer will perform in a similar manner. The hammer illustrated may be of any conventional reciprocating type.

The stirrup means 15 consists of a plate 43 secured to the barrel 21 at its lower end, a stirrup 44 designed to receive the toe end of a foot, and a hinge 45 therebetween. The means 15 serves to provide tool locating and holding means of great convenience and efficiency, the pivot or hinge 45 allowing for relative angular positioning of the tool so that nails can be driven at a desired angle with respect to a surface 46.

The nail hopper 16, as shown, comprises a pair of similar but opposite body parts 47 arranged side by side to form a body having a bottom 48 and upstanding circumscribing walls 49. The bottom 48 is formed with downwardly sloped opposite nail guiding portions 50 which define a slot 51 extending from an intermediate point of the hopper body to the forward or discharge end thereof. The body sections 47 are each provided with a wall 52 and said walls are contiguous from the slot 51 to the rear of the hopper central wall which serves to divide the mass of nails in the hopper during tilting thereof and thereby agitate them to loosen them against compacting. For this purpose, also, one or more pins 53 are fixed to the bottom 48 and stand across the movement path of the nails to further divide them.

An encompassing band 54 holds the body sections 47 in assembly, the front wall 55 thereof being formed with a recess 56 where said wall approaches the slot 51 to provide passage for the heads of nails suspended in the slot and moving toward the escapement means 18.

The hopper is provided with a cover 57 which comprises a relatively stationary part 58 and a hinged part 59. The latter can be lifted to provide access to the interior of the hopper.

The means 17 comprises a pair of structural members 60 arranged longitudinally of the hopper and pivotally connected at 61 to the escapement

means 18. Said members 60 each includes an extension 62 beyond the pivots 61 and one of said extensions bears a cam 63 designed to actuate said escapement means 18. An adjustable stop collar 64 is mounted on the plunger 22, and a pair of links 65 connect the extensions 62 and the stop collar.

It will be evident from the foregoing that for each up and down movement of the plunger in the barrel, the hopper will be tilted between the lowered and raised positions of Figs. 1 and 2; that nails in the hopper will be amply agitated by such movement of the hopper; and that nails finding themselves suspended by their heads in slot 51 will be slid into escapement means 18.

Said escapement means 18 comprises a block or body 66 which is formed with a transverse slideway 67 and with a downwardly sloping portion 68. The latter is bifurcated by a slot 69 that is in alignment with the slot 51 of the hopper so as to receive nails from said hopper as the latter is upwardly tilted. The slope of the portion 68 is such that nails, suspended by their heads, will readily slide toward the slideway 67.

A slide or escapement 70 is arranged in the slideway. A spring 71 normally holds the slide retracted against the cam 63, as best seen in Fig. 6, to bring a recess 72 in the slide into alignment with the slot 69 so that the slide 70 may receive a nail sliding from the portion 68 into the recess 72. The upper face 73 of the slide is so angularly sloped that a nail in the recess will seek to slide therefrom.

During the mentioned nail driving movement of the plunger 22 and the upward tilting of the hopper, the cam 63 will move to project the slide 70 against the pull of spring 71 to transport the nail in recess 72 to a point out of alignment with the body slot 69. The slide 70 is relieved at 74 so as not to disturb the nails in slot 69 during the latter movement of the slide and the body is provided with an offset through opening 75 through which the nail, sliding off the slide face 73, passes into the means 19. Upon upward movement of the plunger, the cam 63 will release the slide 70 and the spring 71 will act to retract said slide to its initial position to receive another nail.

The cam 63 and slide 70 are so related that as plunger 12 starts downward, the lower end of the driver shank 32 will have passed the lowermost point of the edges 21 of guide plates 26 before a nail is released to fall through opening 75.

The means 19 comprises a tube 76 aligned with the opening 75 and the mentioned guide plate 26, a nail dropping through the tube and sliding down between the plates to come to rest against the side of the driver shank 32, as shown in Fig. 2. Upon upward movement of said shank, the nail will fall into the passage 24 and assume a position suspended by the detent means 20.

Said detent means consists of a pair of opposed bearing balls 77, each backed by a resilient and compressible block 78 retained by plugs 79 and urging said balls toward each other against shoulders 80 formed in plates 26. The normal space between the balls 77 is large enough to permit the body of the nail to pass therethrough, but said balls will serve as a separable support for the nail head as the driver encounters the same to spring the ball and drive the nail.

It will be noted that the nail that is driven by the driver is one that had been released prior to the nail released during the operative down-

ward movement of the driver, and that upon upward retraction of said driver, the detent means 20 is empty and, therefore, receptive of the nail resting against the shank of the driver, as above stated. Thus, each time a nail is driven, another nail is released and ready to assume its position in the detent means to be, in turn, driven.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and described, but desire to avail ourselves of all modifications that may fall within the scope of the appended claims.

Having thus described our invention, what we claim and desire to secure by Letters Patent is:

1. In a nailing machine, a nail-driving unit comprising a stationary part and a relatively movable part, a nail hopper carried by the stationary part, means mechanically interconnecting the relatively movable part and the hopper whereby movement of said latter part effects movement of the hopper between a raised and a lowered position, means for receiving nails from the hopper while the same is raised and for guiding nails to the stationary part of the nail-driving unit, an escapement embodied in the latter means for successively releasing nails for movement to said stationary part, and means carried by the interconnecting means for operating the escapement.

2. In a nailing machine, means for driving a nail including a projectible nail-driving element and means for holding a nail in position to be driven by said element upon projection thereof, a nail hopper operatively connected to the driving means and movable thereby between a raised and a lowered position, said hopper assuming a raised position during nail-driving movement of the driving element and thereby discharging nails therefrom, means for receiving the nails thus discharged, and means operatively connected with the driving means for releasing a nail from the receiving means whereby the same is adapted to fall against and be intercepted by the nail-driving element while the same is driving the nail held in the holding means.

3. In a nailing machine, means for driving a nail including a projectible nail-driving element and means for holding a nail in position to be driven by said element upon projection thereof, a nail hopper operatively connected to the driving means and movable thereby between a raised and a lowered position, said hopper assuming a raised position during nail-driving movement of the driving element and thereby discharging nails therefrom, means for receiving the nails thus discharged, and means operatively connected with the driving means for releasing a nail from the receiving means whereby the same is adapted to fall against and be intercepted by the nail-driving element while the same is driving the nail held in the holding means, said intercepted nail, upon retraction of the driving element falling into the nail-holding means to replace the nail that had been driven.

4. In a nailing machine, means for driving a nail including a projectible nail-driving element and means for guiding a nail to a position to be driven by said element upon projection thereof, a nail hopper operatively connected to the driving means and movable thereby between a raised and a lowered position, said hopper assuming a raised position during nail-driving movement of the driving element and thereby discharging nails therefrom, means for receiving the nails thus discharged, and means operatively connected with the driving means for releasing a nail from the receiving means whereby the same is adapted to fall against and be intercepted by the nail-driving element while the same is driving a nail.

5. In a nailing machine, means for driving a nail including a projectible nail-driving element and means for guiding a nail to a position to be driven by said element upon projection thereof, a nail hopper operatively connected to the driving means and movable thereby between a raised and a lowered position, said hopper assuming a raised position during nail-driving movement of the driving element and thereby discharging nails therefrom, means for receiving the nails thus discharged, and means operatively connected with the driving means for releasing a nail from the receiving means whereby the same is adapted to fall against and be intercepted by the nail-driving element while the same is driving a nail.

6. In a nailing machine, a nail-driving unit comprising a stationary part and a relatively movable part, nail-receiving means carried by the stationary part including an escapement for successively releasing nails therefrom, means connected to and movable by the movable part and engaged with the escapement to operate the same each time that the movable part is moved toward the stationary part to effect the mentioned successive release of nails, and means for guiding such released nails to the stationary part and to a position operatively associated with the movable part.
